UNITED STATES PATENT OFFICE.

HUGH W. SANFORD, CHARLES A. GRIFFITH, AND GEORGE E. JONES, JR., OF KNOXVILLE, TENNESSEE, ASSIGNEES TO SANFORD-DAY IRON WORKS, OF KNOXVILLE, TENNESSEE, A CORPORATION OF TENNESSEE.

RAILWAY-CAR.

1,388,486.

Specification of Letters Patent. Patented Aug. 23, 1921.

Application filed December 2, 1920. Serial No. 427,772.

To all whom it may concern:

Be it known that we, HUGH W. SANFORD, CHARLES A. GRIFFITH, and GEORGE E. JONES, Jr., citizens of the United States, residing at 5 the city of Knoxville, in the county of Knox and State of Tennessee, have invented a new and useful Improvement in Railway-Cars, of which the following is a specification, reference being had to the accompanying drawing.

10 This invention relates to an end sill for a car adapted particularly for mining purposes, and the object of the invention is to provide an integral casting which extends entirely across the end of the car to form an 15 end sill, to act as a draw bar, to form the usual bumper, and to provide an effectual means for connection with the usual longitudinal sills thereby stiffening and preventing the frame from twisting out of its rectangular shape and giving extreme rigidity 20 to the construction.

The invention relates to a structure of this kind which will be hereinafter more particularly described and then definitely claimed.

25 In the drawings accompanying and forming part hereof:

Figure 1 is a top plan view of a draw bar bumper and end sill made in accordance with our invention.

30 Fig. 2 is a front elevation with parts broken away.

Fig. 3 is an end view.

Fig. 4 is a section through the line 4—4 of Fig. 1.

35 Referring now to the details of the drawings by letters: A represents an end sill having a bumper B projecting outwardly therefrom, a draw bar element D also projecting outwardly from said end sill and located over 40 said bumper, trusses E, corner stiffeners F and G, and gusset stiffeners H and I, all preferably formed of one integral casting.

The aforesaid bumper B is swelled outwardly as indicated in Fig. 1 of the drawing, 45 as is customary with bumpers of this class and located immediately over the central portion of the bumper is the aforesaid draw bar element D provided with a coupling pin opening D¹ which is directly over a similar opening B¹ of the bumper, a space being left 50 between the draw bar D and the bumper B for the reception of a coupling link, the coupling pin being designed to drop through the openings D¹ and B¹.

The corner stiffeners F and G, which have 55 been described as being part of the integral casting, are adapted to be securely riveted to the usual longitudinal sills J and J¹, the latter being cut away as shown at J² to afford space for the gusset stiffeners H and I. 60

From the foregoing and the accompanying drawings it will be seen that we have provided a one piece steel casting going entirely across the end of the car to provide an end sill, to act as a draw bar, to form the usual 65 bumper, and to provide an effectual means for connection with the usual longitudinal sills. By this construction the structural steel side sills are rigidly braced against twisting and against an end shock as well. 70 This arrangement also provides a stiffened device in the way of a corner angle which is an integral part of the end sill to run back alongside of the structural steel sills and tie the whole construction together in a rigid 75 way against twisting, etc. Not only does the one piece casting provide the rounded bumper, the truss construction for the end, the draw bar for the coupling pins, but the angle members or stiffeners prevent the frame 80 from twisting out of the rectangular shape and gives extreme rigidity to the construction.

What we claim as our invention is:

1. In a structure of the kind described, a 85 one piece casting comprising an end sill, a bumper projecting therefrom, a draw bar element, and corner stiffeners for connection with the longitudinal sills, substantially as described.

2. In a structure of the kind described, a one piece casting comprising an end sill, a bumper projecting outwardly therefrom and having a coupling pin opening, a draw bar element also projecting outwardly from said 95 end sill and having a coupling pin opening in line with the coupling pin opening of the bumper, and corner stiffeners having connection with the longitudinal sills, substantially as described.

3. In a structure of the kind described, a one piece casting comprising an end sill, a bumper projecting outwardly therefrom and having trussed members connecting it with the sill, a draw bar element also projecting 105 outwardly from said end sill, and corner stiffeners for connection with the longitudinal sills, substantially as described.

4. In a structure of the kind described, a one piece casting comprising an end sill extending entirely across the end of the car and having corner stiffeners for connection with the longitudinal sills, a bumper projecting outwardly from said end sill and having trussed members connecting with said sills and also having a coupling pin opening, a draw bar element also projecting outwardly from said end sill and extending over said bumper and having a coupling pin opening in line with the coupling pin opening of the bumper, substantially as described.
5. In a structure of the kind described, a one piece casting comprising an end sill extending entirely across the end of the car and having corner stiffeners for connection with the longitudinal sills, a bumper projecting outwardly from said end sill and having trussed members connecting with said sills and also having a coupling pin opening, a draw bar element also projecting outwardly from said end sill and extending over said bumper and having a coupling pin opening in line with the coupling pin opening of the bumper, and gusset stiffeners between the end sill and said corner stiffeners, substantially as described.
6. In a structure of the kind described and in combination with the longitudinal sills, a one piece casting comprising an end sill extending across the end of the car from one of said longitudinal sills to the other, a bumper projecting therefrom, a draw bar element, and corner stiffeners integral with the end sill and forming a connection between said sill and said longitudinal sills, substantially as described.
7. In a structure of the kind described and in combination with the longitudinal sills, a one piece casting comprising an end sill extending across the end of the car from one of said longitudinal sills to the other, the ends of said sill having corner stiffeners for connection with said sills providing a rigid frame to prevent twisting, a bumper formed integral with said end sill and projecting outwardly therefrom and a draw bar element also formed integral with said sill and projecting outwardly therefrom over the aforesaid bumper, substantially as described.

In testimony whereof we have signed our names this 27th day of November, in the year one thousand nine hundred and twenty.

HUGH W. SANFORD.
CHARLES A. GRIFFITH.
GEORGE E. JONES, JR.
